BEAM RECEIVING SYSTEM BY FREQUENCY
MULTIPLICATIONJozef Plebanski, Warsaw, Poland, assignor to
Radio Corporation of America, New York,
N. Y., a corporation of DelawareApplication February 17, 1930, Serial No. 428,998,
and in Poland March 5, 1929

1 Claim. (Cl. 250—11)

This invention relates to directive antenna systems, and more particularly to such of these which utilize a plurality of aerials, suitably spaced apart, for receiving purposes.

- 5 It is well known in the art that spacing between the individual aerials of such directive receiving systems is a factor which depends upon the wave length of the signal to be received. These systems are usually designed to receive with 10 high efficiency signals incoming from one direction and to discriminate against signals from other directions. Such result is effected by making the phases of the currents induced in the system by the signal incoming from the desired 15 direction additive in character so as to give maximum current density while making the phases of the currents induced by signals from other undesired directions opposite in character so as to cancel out.
- 20 The invention is more fully described in connection with the accompanying drawing wherein, Figure 1 diagrammatically illustrates a pair of vertical antennæ and various directions of waves impinging thereon,

- 25 Figure 2 illustrates one form of the present invention,

Figure 3 is a diagram illustrating the operation of the apparatus shown in Figure 2,

- 30 Figure 4 illustrates an embodiment of my invention utilizing four spaced antennæ,

Figure 5 is a characteristic curve of my arrangement shown in Figure 4, and,

- 35 Figure 6 illustrates a modification of my invention wherein received waves are obtained to lower intermediate frequencies before being frequency multiplied.

40 Referring to Figure 1 of the drawing, there are shown two antennæ A and B spaced apart a distance d . For a wave being received from direction I the currents induced in A and B will be in phase, the resulting total current being twice as great as the current in either one of the two antennæ.

- 45 On the other hand, for a wave incoming from direction III in the plane of the two antennæ, there will be a phase difference in the currents induced in A and B which may be represented by the equation

$$\phi = \frac{2\pi d}{\lambda}$$

50 where "d" is the antenna spacing and λ the wave length. If, now, the spacing is made equal to a half wave length

$$(d = \frac{\lambda}{2})$$

then ϕ will equal 180° and the sum of the currents in the two antennæ will be zero.

Similarly, if "d" equals $\frac{1}{16}\lambda$, ϕ will equal

$$\frac{2\pi d}{\lambda}$$

60

or $22^\circ 30'$ and the sum of the currents induced by the signal coming from direction III will not be zero.

But if we arrange the two antennæ according to the Fig. 2 and by means of arbitrary frequency changers (frequency transformers or valve frequency changers) we step up the frequency 8 times (i. e. 3 times doubling the frequency) then we can prove, that the phase difference between 70 currents in anodes of the valves k , l will be 8 times greater than direct in antennæ I and II.

If we have for instance square law detectors, then the detector current can be shown by the figure

$$I_d = a_1 e + a_2 e^2 + a_3 e^3$$

if $e = A \sin (wt - \phi) + B \sin pt \sin (wt - \phi)$.

$$I_d = a_2 \left[-\frac{A^2}{Z} \cos (2wt - 2\phi) - \right.$$

75

$$\left. AB \sin pt \cos (2wt - 2\phi) \right]$$

80

From the above it is clear that by frequency doubling the phaseshifting is also doubled.

85

It can be proved, that if we have any frequency changing arrangement which increases the frequency 2, 3 . . . n times then the phaseshifting (relative phase) will also be increased 2, 3 . . . n times.

90

Therefore spacing aerials for instance at $d = \frac{\lambda}{16}$ and increasing the frequency according to Fig. 2—8 times we can get the same directional characteristics, as with $\frac{\lambda}{2}$ spacing of aerials, but saving much room.

95

By combining according to Fig. 2 two directional systems having each cardioid reception diagram (Fig. 3) we can get an improved characteristic shown by 1 and 2 on Fig. 3.

100

In this way any systems (or aerials) nondirectional or directional can be combined and the directional characteristic can be improved.

105

Therefore by adequate spacing the used wavelength can be too short.

To obviate this, we can utilize the superheterodyne principle and first of all change the incoming signal to the greater wavelength (Fig. 6).

110

The used heterodyne (one or more) can feed

all circuits at the same time. The intermediate wavelength can then be reduced (frequency increased) by means of frequency changers. The directional results will be the same as above, but 5 the construction will be much plainer and easier. Adjusting the phases of heterodyne to each circuit separately the beam can be rotated.

The increased intermediate frequency can be stepped up to the (ab) original wavelength of signal and then regeneration may be utilized as indicated in Fig. 6.

Referring to Figure 6 in more detail, it will be seen that the intermediate frequency can be stepped up to the same amount as before heterodyning to obtain a frequency which may be represented by the equation $2(V-V_0)=V$, where V is the signal frequency and V_0 the heterodyne frequency. For example, for a signal frequency of 800 kc and heterodyne frequency of 700 kc 20 then $V-V_0=100$ kc and $2^n(100)=2^3(100)=800$ kc. From the foregoing, it will be seen that for three times frequency doubling ($2 \times 2 \times 2=8$ times) of the intermediate frequency 100 kc, there is obtained the same frequency as the original. This frequency can be used to regenerate the receiver upon the input side. Of course, the multiplied output frequency must be the same or about the same as the original signal frequency. Only in this case, this method of regeneration or 30 reaction may be used. By using this kind of reaction on each antenna a still better directional characteristic is obtained. In Figure 6 such arrangement is shown with only two antennas. Of course, any number of antennas may be used.

35

Each antenna or antenna system is associated with one receiver in which the signal frequency is reduced by means of a heterodyne V_0 to the intermediate frequency $V-V_0$ which is then multiplied by means of valves or other arrangements between points c , d and c' , d' until a frequency $2^n(V-V_0)$ is obtained, and if this frequency is equal to the signal frequency V it may be used for regeneration purposes. The combined output is fed to the points a , b .

In this way less quantity of valves can be used.

Furthermore the antennas from Fig. 4 can be for instance combined firstly every two then every three and finally the sum current of all four can be taken.

Using this kind of intercombination with frequency multiplication still better directional characteristics can be got.

With five antennas for instance all $\frac{1}{4} \lambda$ wide by suitable combining and frequency multiplication the same directional characteristic can be got as with $10\frac{1}{2} \lambda$ wide beam receiving aerial.

What is claimed is:

In a radio receiving system, a plurality of spaced antennæ, means for heterodyning the waves collected upon said antennæ to a lower intermediate frequency, means for frequency multiplying the intermediate frequency energy to the frequency of the received wave, means for regeneratively amplifying said frequency multiplied energy, and means for combining the frequency multiplied energy whereby the directive characteristic of said antennæ is improved.
